United States Patent Office

Des. 228,519
Patented Oct. 2, 1973

228,519

SEARCHLIGHT OR SIMILAR ARTICLE

Arthur H. Moore, Fairfield, Conn., assignor to The Bridgeport Metal Goods Manufacturing Company, Bridgeport, Conn.

Filed Feb. 2, 1972, Ser. No. 223,046

Term of patent 14 years

Int. Cl. D26—02

U.S. Cl. D48—24 A

FIG. 1 is a perspective view of a searchlight or similar article showing my new design;

FIG. 2 is a top plan view thereof;

FIG. 3 is a side elevational view thereof;

FIG. 4 is a rear elevational view thereof; and

FIG. 5 is a front elevational view thereof.

I claim:

The ornamental design for a searchlight or similar article, substantially as shown and described.
